SLIDE HOLDER FOR NECKTIES

Darold B. Hickman, North Attleboro, Mass.

Application March 9, 1949, Serial No. 80,530

1 Claim. (Cl. 24—49)

1

This invention relates to a necktie holder and it consists in the constructions, arrangements and combinations herein described and claimed.

It is the cardinal object of the invention to provide a necktie holder wherein the tie encircling members are laterally slideable relative to one another providing an opening between a pair of ends of the members whereby the tie may be positioned within the members so as to encircle the tie and retain the same in a neat and orderly fashion when the encircling members are returned to operative closed positions.

More specifically, it is an object of the invention to provide a tie holding device having a clip device for securement to a shirt front and in which a pair of elongated opposed loops are employed slidably interconnected and including means to limit movement between open and closed positions of the loops, the open position of the loops providing a space between adjacent ends of the loops enabling ready positioning of tie portions between said loops and movement of the loops to closed position encircling the tie portions and retaining them neatly in position on the shirt.

Additional objects, advantages and features of invention will be apparent during the course of the following description, considered in conjunction with the accompanying drawings, wherein

Figure 1 is a front elevation of the tie holder in closed position;

Figure 2 is a rear elevation of a modification;

Figure 3 is a top plan view of Fig. 1;

Figure 4 is a longitudinal sectional view of the tie holder in open position;

Figure 5 is a cross section on the line 5—5 of Figure 4.

There is illustrated a necktie holder generally indicated by the reference character 10 consisting of a pair of elongated loop members 11 and 12 slidably interconnected by means of a sleeve 13, as will be now described, attention being invited to Figure 4 of the drawing.

The loop member 11 has a leg member 14 of a length one-half that of the assembled holder and a short leg 15 fixedly secured in the adjacent end of the sleeve 13, the legs being in substantially parallel relation. The loop member 12 includes a leg 16 of a length corresponding to that of the leg 14 and has secured thereon any suitable ornament 17. The loop 12 also has a long leg 18 substantially parallel to the leg 16, disposed slidably in the sleeve 13. The outer face of the leg 18 is provided with a groove 19 extending medially and longitudinally thereof and the sleeve 13 is

2

formed with an inwardly projecting nodule 20 complementary to the groove 19. The groove 19 terminates inwardly of the extremity of the leg 18 defining a stop 21 limiting outward movement 5 of the leg from the sleeve. The leg 18 is of such length so as to stop short of the leg 15 of the loop member 11 when the loop members 11 and 12 are in their closed positions.

A sleeve 22 is secured to the leg 18 adjacent 10 the bight 23 of the loop, the sleeve being formed with an opening 24 into which an end of a spring clip 25 may be seated and secured to the leg 18 and the sleeve 22 by soldering or otherwise. The length of the sleeve 22 will be such as to abut 15 the opposed end of the sleeve 13 when the legs 14 and 16 are brought into end to end relation, as clearly shown in Figure 3.

It will be noted that the plate 17 is secured to the leg 16 with a thickness of solder to space the 20 plate out of alignment with the leg 14 to permit free sliding movement.

In use, the leg 18 of the loop 12 is partially withdrawn through the sleeve 13 until the nodule 20 engages the stop 21, as illustrated in Figure 4. 25 The clip 25 is then engaged with the shirt hem at the height desired by the user, and respective portions of a tie may then be inserted edgewise between the spaced ends of the legs 14 and 16 as indicated by dotted lines in Figure 4. When the tie portions are arranged between the legs 14 and 16 and the leg 18 and sleeve 13, the loop 12 is moved in the direction of the loop 11, causing the leg 18 to move into the sleeve 13 until such movement is stopped by engagement between the ends 30 of the sleeves 13 and 22 and respective ends of the legs 14 and 16.

To remove the tie portions from the loop members a reverse of the above operation would be involved.

40 While I have shown and described a preferred form of the tie holder, this is by way of illustration only, and I consider as my own all such modifications in construction as fairly fall within the scope of the appended claim.

45 I claim:

A holder for portions of a necktie comprising 50 a pair of loop members, one loop member having a long leg member and a short leg member in substantially parallel relation, a sleeve fixed to the short leg member, the other of said loop members having a long leg member disposed slidably within said sleeve, the other leg of said last named loop member corresponding in length to that of the long leg member of said first named loop member and extending in substantially parallel

relation thereto, the ends of said last named legs adapted to abut upon inward sliding movement of said leg within the sleeve, means between the sleeve and the leg therewithin for limiting outward sliding movement of the leg, a clip device secured to said last named leg, and an ornamental plate affixed to one of said abutting leg members and projecting therebeyond for overlapping relation with the opposed leg member.

DAROLD B. HICKMAN.
